HOLY WATER FOUNTAIN

Stanley Laskowski, Beaver Falls, Pa.

Filed Nov. 13, 1961, Ser. No. 67,495

Term of patent 3½ years

(Cl. D29—23)

FIG. 1

The broken line showings in FIGURE 1 are for illustrative purposes only.

I claim:

The ornamental design for a holy water fountain, as shown and described.
